UNITED STATES PATENT OFFICE.

HAROLD WILLIAM SANDERSON, OF LONDON, ENGLAND.

PRINTING WALL-PAPER.

SPECIFICATION forming part of Letters Patent No. 569,237, dated October 13, 1896.

Application filed August 20, 1894. Serial No. 520,835. (No model.) Patented in England May 30, 1894, No. 10,529, and in France July 30, 1894, No. 240,394.

To all whom it may concern:

Be it known that I, HAROLD WILLIAM SANDERSON, manufacturer of paper-hangings, a subject of the Queen of Great Britain and 5 Ireland, and a resident of Chiswick, London, England, have invented certain new and useful Improvements in and Relating to the Printing of Wall-Papers, applicable also to the printing of posters, textile fabrics, and the 10 like, (for which I have obtained a patent in Great Britain, No. 10,529, dated May 30, 1894, and in France, No. 240,394, dated July 30, 1894,) of which the following is a specification, reference being had to the accompanying 15 drawing, which represents in side elevation and partly in section the arrangement of the different parts.

In carrying my invention into practice I construct a pair of opposite side frames of 20 any suitable material and having any desired shape or form, which side frames are adapted by means of bearings to carry a shaft A, upon which a suitably-constructed drum B is mounted. At a suitable part of said side 25 frames I provide a pair of opposite sliding bearings C, the arrangement of the slides being such that the said bearings C may be adjusted in any desired direction relative to the drum B. Said bearings C serve to support a 30 spindle E, upon which a printing-roller F is mounted, which printing-roller is formed or provided on its periphery with any desired design engraved so as to leave the design in relief, or any required design may be reproduced 35 from the wood engraving by stereotype, electrotype, or other well-known method and mounted on the printing-roller, or any suitable design may be produced by any well-known process, such as zincograph and photo 40 process, and mounted on the printing-roller. In convenient proximity to the said printing-roller F, I provide a "duct" or "fountain" G, which is adjusted with a suitable ink-roller H, adapted to be revolved as hereinafter 45 described, and vibrator K. Said duct or fountain G is adapted to receive the printing-ink or the lithographic ink sufficiently thinned down, and for the purpose of regulating the supply of such ink to the ink-roller H said 50 duct is constructed so that a "knife" or the like L may, by means of set-screws M, be set

farther from or closer to the said ink-roller H, so as to allow a greater or less quantity of such ink to be carried on said revolving ink-roller. Said roller H receives its rotating 55 motion from the pitch-wheel or other suitable source by means of suitable gearing in the usual manner, and for the purpose of imparting vibratory movement to the vibrator K, I form or provide one of the gear-wheels referred 60 to with an arm N, by means of which the rearwardly-extending end O of the rocking frame P is depressed and consequently the opposite end of said rocking frame, which carries the vibrator K, is raised until the said 65 vibrator K comes in contact with the ink-transmitting roller Q, so that comparatively only a small quantity of ink is transferred from the duct G to the roller Q.

For the purpose of obtaining an even distribution of the ink on the roller Q, I provide two or more ink-distributing rollers Q', and I prefer also to cause the roller Q to vibrate in the direction of its length, and for the purpose of inking the printing-roller F, I provide 70 two or more inking-rollers R, which are in contact both with the ink-transmitting roller Q and the printing-roller F, as shown, and in order to further insure an even distribution of the ink onto the printing-roller 75 F, I prefer to provide one or more additional inking-rollers R', which receive their ink from the inking-rollers R by means of one or more intermediate rollers R².

The diameter of the printing-roller F depends upon the length of the pattern or design being printed, and in order that within reasonable limits a printing-roller of any desired diameter may be used I provide the sliding or adjustable bearings C, as hereinbefore described. The rollers Q Q' R R' R² are also supported in adjustable bearings, so that they may be adjusted and set to suit a printing-roller of larger or smaller diameter.

The drum B serves to support the paper or 95 textile fabric S while being printed, and in order that the pressure of the printing-roller F against the paper or textile fabric shall not injure the latter, and also so that all the fine lines may be more readily printed, I dispense with the usual comparatively thick 100 blanket or felt, which is wound around the

drum, and fix to said drum any suitable thin material, or if found requisite such thin material may be dispensed with, so that the surface thereof will be comparatively hard, 5 in place of the soft surface hitherto employed in the printing of wall-papers by means of raised rollers, thus making the drums larger in comparison with drums hitherto used.

Having now described my invention, what

10 I claim as new, and desire to secure by Letters Patent, is—

15 1. In a wall-paper-printing machine the combination of a duct G provided with a knife L and screws M, ink-roller H adapted to receive rotary motion, ink-carrying rollers Q, ink-distributing rollers Q', inking-rollers R, R', intermediate roller R², printing-roller F and vibrator K carried by a rocking frame P adapted to be vibrated by means of an 20 arm N on the gearing, all for the purposes and substantially as set forth.

2. In a wall-paper-printing machine having an ink-roller H which is adapted to receive

rotary motion, ink-carrying rollers Q, ink-distributing rollers Q', inking-rollers R, R', 25 intermediate rollers R² and printing-rollers F, the combination therewith of a duct G having a knife L and set-screws M by means of which set-screws and knife the quantity of ink supplied onto the ink-roller H may be 30 regulated, and a vibrator K carried by a rocking frame P adapted to have rocking motion imparted to it by means of suitably-supported arms N which are adapted to depress the rear end O of said rocking frame and thereby 35 raise the opposite and vibrator-carrying end so that said vibrator is made to intermittently come in contact with the ink-transmitting roller G, all for the purposes and substantially as set forth. 40

In witness whereof I have hereunto set my hand in presence of two witnesses.

HAROLD WILLIAM SANDERSON.
